OF BROOKLYN, NEW YORK.

COMPUTING-MACHINE.

1,146,371.

Specification of Letters Patent. Patented July 13, 1915.

Application filed August 17, 1911. Serial No. 644,573.

To all whom it may concern:

Be it known that I, JOHN N. THORNTON, a citizen of the United States, residing in Jersey City, in the county of Hudson and State of New Jersey, have invented certain new and useful Improvements in Computing-Machines, of which the following is a specification.

This invention relates to power drives adapted for computing machines, and especially to combined typewriting and computing machines, of the class shown in co-pending applications of Frederick A. Hart, Frank Allard and Fred F. Main, in which is shown an Underwood-Hanson typewriting and adding machine, in which the numeral keys of the typewriter are caused to set up pins which are subsequently engaged by a general operator, whereby the extent 20 of rotation of the dial wheels is determined. The general operator is actuated by an electric motor, and the present improvements relate to means for controlling the motor as well as for controlling its connection to the 25 general operator. Certain features of the invention are also applicable to other machines, in which a motor is employed in connection with other devices than a general operator.

One of the principal features of the present improvements consists in the provision of means for closing a circuit through the motor, and connecting it to the computing mechanism. Not only is the motor circuit 30 normally open, but the motor is also normally disconnected from the computing mechanism.

In carrying out the invention, I preferably employ a self-closing circuit and a self-closing clutch. These self-closing devices are restrained by means of a latch; and a key at the keyboard, or any suitable device, may be provided for closing the motor circuit, and concomitantly closing the 45 clutch. Included in the motor circuit are two primary elements, one in the nature of a bridge, and the other in the nature of a pair of brushes or contacts; and one of the contacts is normally opposite a gap which is 50 provided in the bridge, so that no current flows through the motor. A spring, however, tends to move one of said primary elements to close the circuit; and this spring is normally restrained by a latch. By depressing a key, the latch is moved, and the 55 spring operates to rotate one of said pri-

mary elements sufficiently to close the circuit. The circuit remains closed during the ensuing cycle of movements of the computing mechanism; and at the conclusion of 60 said cycle, the circuit is again opened. The clutch is under the control of a ring or collar or member, which has a slip connection to the motor; and whenever the latter is in operation, tends to rotate said controlling 65 member in a manner to close the clutch. The latch aforesaid, however, is arranged to hold said controlling member in clutch-releasing position; but when said latch is withdrawn and the circuit is closed, there is nothing to 70 prevent the clutch from being closed by the movement of the motor. At the conclusion of said cycle of operations of the computing mechanism, the clutch also is opened, so that the parts resume their normal positions. 75

Certain features of the circuit-closing mechanism are available in other machines in which the motor is otherwise connected to the mechanism than through a friction 80 clutch.

Other features and advantages will hereinafter appear.

In the accompanying drawings, Figure 1 is a sectional elevation of an Underwood-Hanson combined typewriting and computing machine, of the kind to which the above improvements are applied. Fig. 2 is a sectional side elevation of the circuit and clutch-closing members, showing them in 85 normal positions. Fig. 3 is a side elevation of a pair of brushes and the device upon which they are mounted. Fig. 4 is a perspective view of a disk, which is used for supporting and operating a rotary bridge. 90 Fig. 5 is a perspective view similar to Fig. 2, but showing the latch withdrawn and the circuit closed. Fig. 6 is a sectional front elevation through the clutch mechanism, which is arranged below the frame of the 95 computing mechanism. Fig. 7 is an elevation of the clutch ring, seen at Figs. 2 and 5.

An intermittently operated electric or other motor 1 is provided with a main shaft 105 2, the latter preferably connected to a shaft 3 by means of a safety friction clutch. This clutch may comprise a disk 5 having a hub 4 keyed to the shaft 2, a friction disk 6 being loose on said hub; another friction disk 110 7 being confined between disks 5 and 6. An arm 8 fast on shaft 3 is bent over at 9

to be engaged and driven by a lug 10 on disk 6. A compression spring 11 is coiled around the hub 4, and adjusted by a nut 12 to determine how much of a load the clutch will 5 carry without slipping.

A rack 13, forming part of a rack frame, is movable forwardly and backwardly in the base of the adding machine, and performs the final portion of the computing 10 operation. This rack frame is reciprocated intermittently by the rotating shaft 3, by means of a clutch mechanism; said rack frame being connected to a crank shaft to be driven thereby, and the crank shaft being 15 connected by a worm gearing to said shaft 3, as will presently be set forth.

Upon the rack frame is secured a yoke or carrier 14, in engagement with which is the upper end of an arm 15, provided on a cross 20 head 16, which moves forwardly and backwardly, or from left to right at Fig. 1, and return so as to reciprocate said rack frame 13; said cross head being carried on a horizontal slide 17, which works in bearings 25 18 on a casing 19. This slide is reciprocated by means of a crank 23, fixed on a horizontal shaft 24; said crank carrying a slide block 26, working in a groove 27 in the cross head.

Loose on shaft 24 is a worm gear 30 mesh- 30 ing with a worm 31, the latter fixed on shaft 3, so that the worm gear or wheel 30 may be intermittently rotated. The worm wheel 30 is connectible to shaft 24 to turn the same whenever it is necessary to reciprocate the 35 rack frame 13 to complete a computing operation; and at the conclusion of said reciprocation, said worm wheel 30 is automatically disconnected from the shaft 24, and the latter comes to a stop, together with the 40 motor by means now to be explained.

Fixed to crank shaft 24 is a cupped member 32 of a clutch. The hub of worm gear 30 is designated as 33. The clutch also comprises gripping rolls 34 to run upon 45 opposite sides of the gear wheel hub 33, Fig. 2. These rolls normally occupy pockets 35 in the clutch cup, said pockets having inclined walls against which the rolls may wedge, although the rolls are normally released. The clutch rolls are shiftable between gripping and releasing positions in the pockets 35 by means of a ring 36 fitted 50 upon the gear hub 33 to be independently rotatable and occupying a position within 55 the cup 32. This ring 36 has cutaways or recesses 36^a to receive loosely the balls 34, so as to control the latter. The ball-controlling ring 36 is frictionally connected to the gear hub 33 by means of a double spring 37 60 secured to the ring by a screw 37^a and pressing pins 37^b through perforations in the ring 36 against the surface of gear hub 33. This device enables the hub to take a fairly 65 strong grip upon the ring, so that the latter always tends to rotate with the hub.

This tendency is in a direction to close the clutch; and hence when the motor is rotating there is a constant tendency to close said clutch. Normally however said ring 36 is restrained from causing the rolls to 70 bind; or in other words said ring is normally held in clutch-releasing position. For this purpose there is provided a trip pin or latch 40 normally in the path of a lug 41 provided upon the releasing ring 36, said 75 lug 41 projecting through an opening 41^a in the clutch cup 32. Whenever the crank shaft 24 is to be clutched to the gear 30, the latch 40 is raised to release the lug 41 to permit the gear hub 33 (assuming the 80 latter to be rotating) to carry around both the ring 36 and the rolls 34 until the latter grip upon the inclined walls of the pockets 35, thereby closing the clutch. The pin 40 is immediately dropped again into the path 85 of lug 41, so that at the completion of a single revolution of the shaft 24, the latter is again unclutched automatically from the worm gear 30. The latch 40 is also employed for the purpose of controlling the 90 motor circuit, closing said circuit, and then opening the same. The circuit is closed by the upward movement of the latch 40, which withdraws it from the path of the clutch-releasing lug 41. When said latch 40 is 95 lifted, a spring 42 in said lug, by pressing against an ear 43 on a disk 44, Fig. 4, imparts to the latter a slight advance rotation; said disk 44 being, for convenience, loosely mounted upon the hub 45 of the clutch ring 100 32, Fig. 6. Said latch 40 and ear 43 project through an opening 35^a in said cup member 32. This starting forward of said disk 44 is utilized for the purpose of closing the circuit through the motor 1. Upon said 105 disk 44 is carried a circular or disk-like bridge 46, and against the outer face of 46 press yielding brushes or contacts 47, 48 in the form of fingers secured upon a disk-like support 49 of insulating material and 110 connected by arms 50 to conductors 51, the latter directly connected with the motor 1. The tip 52 of the finger 48 rests normally upon an insulating plug 53 filling the recess 54 in the annular bridge 46; while the 115 other finger 47 is constantly in contact with said bridge, being so short as to escape said recess 54, as will be understood from Fig. 3.

It will be noticed that the bridge 46 is 120 secured by screws 55 upon the outer face of an insulating disk 56, which is attached in any suitable way to the outer face of said disk 44, the members 44, 56 and 46 being rigidly secured together.

It will now be understood that when the spring 42 moves the bridge disk 44 from the normal position at Fig. 2 to the position at Fig. 5, the tip 52 of contact 48 stands in contact with the bridge 46, so that a cir- 130

cuit is completed through the latter, and through the brush or contact to the motor, and hence the latter revolves. The revolution of the motor, as already explained, turns the clutch-controlling ring 36 to cause the rolls 34 to bind the gear hub 33 to the clutch ring 32; and all of these members rotate together until a complete revolution is effected of the gear 30. In the meantime the latch pin 40 is dropped into the path of the ear 43, and arrests the latter when the tip 52 is resting upon the insulating plug 53, and hence the motor circuit is broken. The motor however continues to revolve by means of its momentum, and through the friction plugs 37^a causes the clutch ring 36 to complete its revolution to the Fig. 2 position, thereby compressing the spring 42. At the same time, all of the parts are brought to their normal Fig. 2 positions, the balls 34 becoming unclutched from the cup 32 substantially as shown. The motor, by reason of its momentum, may continue to rotate idly.

It will be seen that, although the motor circuit is closed and opened, still the movements of the crank shaft 24 are not co-extensive with the movements of the motor, since the latter may run idly after the crank shaft comes to rest. In other words, the crank shaft is given a predetermined movement, notwithstanding that it is driven by the motor whose movement is not of the same duration as that of the crank shaft, this discrepancy being permitted, by reason of the clutch mechanism, which is controlled by the latch 40 that also controls the motor circuit.

The rack frame 13 is caused to reciprocate after the numeral keys of the typewriter have been operated to set up a number. This rack frame operates to turn the computing wheels to different extents, depending upon the key operated. In some cases, the described clutch is operated after each number is written on the typewriter. There is shown a special key or handle to operate said clutch, and cause a reciprocation of the rack frame, this special key being substantially the same as shown in pending application of Frederick A. Hart No. 607,925, filed February 11, 1911. Said key is designated as 57, and is mounted on a stem 58 pivoted at its lower end to a lever 59 fulcrumed at 60 upon the machine frame. Said lever in turn, depresses a cross lever 61 which is pivoted at 62 to the framework, and at its other end engages a notch 63 formed in the top of the trip pin or latch 40, so as to cause and control the up and down movement of said latch, whereby the clutch is caused to open and close. Depression of the key 57 carries down the lever 59; the latter rocks the lever 61 about its fulcrum 62, the other end of the lever lift-

ing the latch 40 away from the clutch dog 41 and the bridge gear 43. The operator then immediately releases the key 57, which is returned to normal position by a spring 69. The lever 61 has a returning spring 62^a.

The typewriter includes the usual set of type-operating keys, including alphabet keys and also including numeral keys 88 mounted on levers 88^a and connected by bell cranks 89 to type bars 90, which are thrown back against a platen 91 mounted on a carriage 92. The carriage is power-driven, as usual, and has a rack 87 meshing with a pinion 86, connected with an escapement wheel 85, the latter controlled by dogs 84, 80 operated by a universal bar 83, which is actuated by the type bars, so that whenever any type key is actuated, the carriage 92 is caused to feed a letter space.

Fastened at the back of the carriage 92, 85 are brackets 93, carrying a rack 94, to receive adjustable cams or tappets 95. Whenever any tappet, during the travel of the carriage, passes beneath the set of jacks 96, it raises the forward ends of the jacks in succession, turning each on its pivot 97, and depressing its rear end to press down the corresponding one of a set of wires 98. These wires are connected at their lower ends to levers 99 on a fulcrum rod 100. 90 Each lever 99 raises one of a set of linkages 101, each linkage having a pin 102 to lift the rear end of a rack 103, the forward end of which meshes with a pinion 104 connected to a computing wheel 105. Each rack 100 carries a set of pins 106, and one of these is depressed by the operated type key 88; each key having a stem 110, for this purpose, to depress a crank 112, fast to a shaft 113, which is connected to a linkage 114, to depress one of the pins 106 upon the lifted rack bar 103; there being one linkage 114 for each key, each linkage being in position to depress a corresponding pin 106 on whichever rack bar is lifted, as set forth in 110 said application. After the keys 88 are manipulated to write a number, and the corresponding racks 103 accordingly elevated as the paper carriage feeds along, and certain pins 106 thereon depressed, there must 115 be caused a reciprocation of the rack frame 13. This frame usually includes a pair of arms 115 connected by a transverse horizontal bar 116, which is in position to engage all the displaced pins 106, and to give corresponding forward endwise movements to their racks 103, thereby turning the computing wheels 105 accordingly; the return movements of the racks not turning said wheels, however, because of a pawl-and-ratchet connection (not shown) between said wheels and their drive pinions 104. Pinions 106^a meshing with racks 13, are also in mesh with segments 116^b fixed on rock shaft 116^c, and if desired said rack frame 13 may be 120 125 130

manually reciprocated by said rock-shaft 116° when the arm 15 is disconnected from the computing mechanism.

Variations may be resorted to within the scope of the invention, and portions of the improvements may be used without others.

Having thus described my invention, I claim:

1. The combination of the machine proper, 10 a motor for driving the same, a clutch between the motor and the machine, normally remaining ineffective, but adapted to be made effective when the motor is turning, a controlling device for said clutch, and means for concomitantly starting and stopping the motor and operating said controlling device for connecting and disconnecting said clutch.
2. The combination of the machine proper, 20 a motor for driving the same, a clutch between the motor and the machine, normally remaining ineffective, but adapted to be made effective when the motor is turning, a controlling device for said clutch, and means 25 for concomitantly starting said motor and operating said controlling device for connecting said clutch, so as to concomitantly connect said machine to be clutched into driven relation with the motor and excite 30 the motor to action.

3. The combination of the machine proper, a normally silent motor for driving the same, a normally open clutch between the motor and the machine, but adapted to be 35 closed when the motor is turning, a controlling device for said clutch, and a common means for operating said device for closing said clutch and starting said motor.

4. The combination of the machine proper, 40 a motor for driving the same, a clutch between said motor and said machine, said motor having a normally open circuit, means tending to close said circuit, a latch restraining said closing means, means operated from said machine for withdrawing 45 said latch to permit said circuit-closing means to operate, means dependent on the movement of the motor for closing said clutch, and means for returning said latch 50 to normal position to effect the opening of the circuit and adapted to release said clutch.

5. The combination of the machine proper, a normally silent motor for driving the same, a clutch between said motor and said 55 machine, said motor having an open circuit, means dependent on the movement of the motor for closing said clutch, means including a spring tending to close said circuit, and a latch restraining said closing means, 60 said machine having a key connected to withdraw said latch so as to permit said circuit-closing and clutch-closing means to operate.

6. The combination of the machine proper, 65 a normally silent motor for driving the

same, said motor having an open circuit, a clutch between said motor and said machine, means dependent on the movement of the motor for closing said clutch, means including a spring tending to close said circuit, a latch restraining said closing means, said machine having a key connected to withdraw said latch so as to permit said circuit-closing means to operate, means for returning said latch to normal position to effect the opening of said circuit and the release of said clutch, and means dependent upon the operation of said motor for retensioning said spring.

7. The combination of the machine proper, 80 a normally silent motor for driving the same, said motor having a normally open circuit, a clutch between said motor and said machine, means dependent on the movement of the motor for closing said clutch, means tending to close said circuit, said closing means including a revolute device, a connection between said revolute device and said motor permitting the latter to rotate independently of the closing device, a latch restraining said closing means, and means for withdrawing said latch to permit said circuit-closing means to operate.

8. The combination of the machine proper, 85 a motor for driving the same, said motor having a normally open circuit so as to be normally silent, means tending to close said circuit, said circuit-closing means including a revolute device, a frictional or slipping connection between said revolute closing device and said motor permitting the latter to rotate independently of said closing device, a latch restraining said closing means, means operable from said machine proper 90 for withdrawing said latch to permit said circuit-closing means to operate, and means for returning said latch to normal position to effect the opening of the circuit.

9. The combination of the machine proper, 110 a motor for driving the same, said motor having a normally open circuit, so as to be normally silent, a circuit-closing means including, as two primary elements, a bridge and a pair of contacts or brushes, one of said primary elements mounted for revolution with said motor and one of said brushes normally opposite a break in said bridge, whereby the motor circuit is normally open, and means controllable from said machine proper to effect a relative movement between said primary elements to close the circuit.

10. The combination of the machine proper, a motor for driving the same, said motor having a normally open circuit so as to be normally silent, a circuit-closing means for said motor including, as two primary elements, a bridge and a pair of contacts or brushes, one of said primary elements mounted for revolution with said motor and 120

- one of said brushes normally opposite a break in said bridge, whereby the motor circuit is normally open, means controllable from said machine proper to effect a relative movement between said primary elements to close the circuit, and said primary elements coöperating to keep the circuit closed during substantially an entire revolution of the revolving primary element, and 10 means to arrest the revolving primary element when it again reaches normal circuit-breaking position.
11. The combination of the machine proper, a motor for driving the same, said 15 motor having a normally open circuit so as to be normally silent, circuit-closing means including, as two primary elements, a bridge and a pair of contacts or brushes, one of said primary elements mounted for 20 revolution with said motor and one of said brushes normally opposite a break in said bridge, whereby the motor circuit is normally open, means controllable from said machine proper to effect a relative movement 25 between said primary elements to close the circuit, a slip connection or friction device to connect said revolving primary element to said motor, and means to arrest the revolving primary element when 30 it again reaches normal circuit-breaking position.
12. The combination of the machine proper, a motor for driving the same, said 35 motor having a normally open circuit so as to be normally silent, primary elements, one of which comprises a pair of brushes and the other of which comprises a bridge to be engaged by said brushes, one of said primary elements being included in said circuit, said bridge having a gap normally opposite one of said brushes whereby said circuit is normally open, a spring normally tending to move one of said primary elements to close said circuit, means restraining 40 said last-mentioned primary element, means operable from said machine proper to withdraw said restraining means, one of said primary elements having a slip connection with said motor to revolve there- 45 with, and means whereby said restraining means may be returned prior to the conclusion of the cycle of operations of the machine proper to a position to intercept the revolving primary element and tension said 50 spring.
13. The combination of the machine proper, a motor for driving the same, said 55 motor having a normally open electric circuit so as to be normally silent, a pair of brushes, a bridge in said circuit to be engaged by said brushes, said bridge having a gap normally opposite one of said brushes whereby said circuit is normally open, a spring normally tending to move said bridge 60 to close said circuit, a latch for restraining 65
- said bridge, a clutch controlled by said bridge and between said motor and said machine comprising a member adapted to drive said bridge by said spring, and means controllable from said machine proper for 70 withdrawing said latch.
14. The combination of the machine proper, a motor for driving the same, said 75 motor having a normally open circuit, a pair of brushes, a bridge in said circuit to be engaged by said brushes, said bridge having a gap normally opposite one of said brushes, whereby said circuit is normally open, a spring normally tending to move the bridge to close the circuit, a latch to restrain 80 said bridge, means controllable from said machine proper to withdraw said latch, a clutch controlled by said bridge and between said motor and said machine comprising a member adapted to drive said 85 bridge by said spring, and means automatically returning said latch to its normal position in the path of said bridge.
15. The combination of the machine proper, a motor for driving the same, said 90 motor having a normally open circuit so as to be normally silent, a pair of brushes, a bridge in said circuit to be engaged by said brushes, said bridge having a gap normally opposite one of said brushes, whereby said 95 circuit is normally open, a clutch between said motor and said machine comprising a dog having a slip connection with said motor, a spring between said dog and said bridge normally tending to move said bridge 100 to close said circuit, a latch to restrain said dog and said bridge, and means controllable from said machine proper to withdraw said latch.
16. The combination of the machine proper, a motor for driving the same, said 105 motor having an electric circuit normally open so that said motor will be normally silent, a shaft revoluble by said motor and connected to drive said machine, a collar on said shaft, a friction device between said collar and said shaft, a dog on said collar, a spring having a bearing on said dog, a bridge movable independently of said dog and of said shaft, an ear on said bridge, 110 said spring having a bearing on said ear, a latch in the path of said ear to hold said spring under tension, means operable from said machine proper to release said latch, and a pair of brushes to engage said bridge, 115 one of said brushes being normally opposite a gap in said bridge, said bridge being movable by said spring to a position to be engaged by said last-mentioned brush.
17. The combination of the machine proper, a motor for driving the same, said 120 motor having a normally open, self-closing electric circuit, a normally open, self-closing clutch between said motor and said machine proper, means normally restraining said 125

18. The combination of the machine proper, a motor for driving the same, a normally open, self-closing electric circuit for said motor, a normally open, self-closing clutch device between said motor and said machine proper, means normally restraining said circuit and said clutch device from closing, means controlled from said machine proper for withdrawing said restraining means, and means to return said withdrawing means to normal position.
19. The combination of the machine proper, a motor for driving the same, said motor having a normally open, self-closing electric circuit, a normally open, self-closing clutch device between said motor and said machine, means normally restraining said circuit and said clutch device from closing, means controlled from said machine proper for withdrawing said restraining means, means to return said withdrawing means to normal position, and means dependent upon the revolutions of the motor for completing the cycle of operations of said machine and opening the clutch and circuit.
20. The combination of the machine proper, a motor for driving the same, a normally open, self-closing circuit for said motor, a normally-open, self-closing clutch device between said motor and said machine, said circuit and said clutch device including a part dependent upon the rotation of the motor to effect the closing of the clutch device, means normally restraining said circuit and said clutch device from closing, and means operable from the machine proper for withdrawing said restraining means.
21. The combination of the machine proper, a motor for driving the same, a normally open electric circuit for said motor, a normally open clutch between said motor and said machine, a single latch for controlling the closing of both said clutch and said circuit, a key for said latch, and means whereby said latch opens both said circuit and said clutch and arrests said machine.
22. The combination of the machine proper, a motor for driving the same, a circuit for said motor normally open, a normally open clutch between said motor and said machine, means to close said circuit, means dependent upon the revolution of said motor for closing said clutch, and a latch removable to close the circuit and adapted to simultaneously open said circuit and arrest said machine.
23. The combination of the machine proper, a normally silent motor for driving the same, a clutch between said motor and said machine, a motor-driven shaft, a collar loose on said shaft and forming a part of said clutch, a slip connection provided between said collar and said shaft, a clutch roll controlled by said collar, a member having a clutch wall converging toward the periphery of said shaft to cause said roll to bind upon said shaft, means for restraining said collar from turning with said shaft, and means controlled from said machine proper for withdrawing said restraining means.
24. The combination of the machine proper, a motor for driving the same, said motor having a normally open circuit, means tending to close said circuit, a latch restraining said closing means, means operable from said machine proper to permit said closing means to operate, means for returning said latch to normal position to effect the opening of said circuit, an automatically closing and opening clutch between said motor and said machine operated by said latch, and means dependent on the operation of the motor for causing said clutch to seize.
25. The combination of the machine proper, a motor for driving the same, said motor having a normally open circuit so as to be normally silent, circuit-closing means including, as two primary elements, a bridge and a pair of contacts or brushes, one of said primary elements mounted for revolution with said motor and one of said brushes normally opposite a break in said bridge, whereby the motor circuit is normally open, means to effect relative movement between said primary elements to close the circuit, and an automatically closing and opening clutch between said motor and said machine.
26. The combination of the machine proper, of a motor for driving the same, said motor having a normally open electric circuit whereby said motor is normally silent, an automatically closing and opening clutch between said motor and said machine, a pair of brushes, a bridge in said circuit to be engaged by said brushes, said bridge having a gap normally opposite one of said brushes, whereby said circuit is normally open, a spring normally tending to move said bridge to close said circuit, a latch for restraining said bridge, said clutch between said motor and said machine comprising a member adapted to drive said bridge by said spring, and means controllable from said machine proper for withdrawing said latch.
27. The combination of the machine proper, a motor for driving the same, an electric circuit for said motor, a shaft revolute by said motor and connected to said machine, a ring or collar on said shaft, a friction device for said clutch between said collar and said shaft, a dog on said collar, a spring having a bearing on said dog, a bridge movable independently of said dog and of said shaft, an ear on said bridge, said spring having a bearing on said ear,

a latch in the path of said ear to hold said spring under tension, means controllable from said machine proper for releasing said latch, a pair of brushes to engage said bridge, one of said brushes normally opposite a gap in said bridge, said bridge being movable by said spring to a position to engage said last-mentioned brush, and an automatically closing and opening clutch between said motor and said machine proper.

28. The combination of the machine proper, a motor for driving the same, said motor having a normally open circuit, a normally open clutch between said motor and said machine, means tending to close said circuit, means dependent on the movement of the motor for closing said clutch, a latch restraining said circuit-closing means, means operable from said machine proper for withdrawing said latch to permit said clutch to close and said circuit-closing means to operate, and means for returning said latch to normal position to effect the opening of said circuit.

29. The combination of the machine proper, a motor for driving the same, said motor having a normally open circuit, a normally open clutch between said motor and said machine, means tending to close said circuit, means dependent on the movement of the motor for closing said clutch, a latch restraining said circuit-closing means, means operable from said machine proper for withdrawing said latch to permit said clutch to close and said circuit-closing means to operate, and means for returning said latch to normal position to effect the opening of said circuit and the opening of said clutch.

30. The combination of the machine proper, a motor for driving the same, said motor having a normally open circuit, so as to be normally silent, a normally open clutch between said motor and said machine proper, means including a spring tending to close said circuit, means dependent on the movement of the motor for closing said clutch, a latch restraining said circuit-closing means, said machine proper having a key connected to withdraw said latch so as to permit the closing of said circuit and said clutch, means for returning said latch to normal position to effect the opening of said circuit, and means dependent upon the operation of said motor for retensioning said spring.

31. The combination of the machine proper, a motor for driving the same, said motor having a normally open circuit, a normally open clutch between said motor and said machine proper, means tending to close said circuit, means for closing said clutch including a revoluble device and a clutch roll engaged thereby, a connection between said revoluble closing device and

said motor permitting the latter to rotate independently of the closing device, a latch restraining both of said closing means, and means operable from said machine proper for withdrawing said latch to permit the closing of said circuit and said clutch.

32. The combination of the machine proper, a motor for driving the same, a normally open circuit for said motor, a normally open clutch between said motor and said machine proper, means tending to close said circuit, means for closing said clutch, said circuit-closing means including a revoluble device, a frictional or slipping connection between said revoluble closing device and said motor, a latch restraining said circuit-closing means, means operable from said machine proper for withdrawing said latch to permit the closing of said circuit, said clutch including a friction roll controlled by said revoluble device, and means for returning said latch to normal position to effect the opening of said circuit.

33. The combination of the machine proper, a motor for driving the same, said motor having a normally open circuit so as to be normally silent, a normally open clutch between said motor and said machine proper, circuit-closing means including, as two primary elements, a bridge and a pair of contacts or brushes, one of said primary elements mounted for revolution with said motor and one of said brushes normally opposite a break in said bridge, whereby the motor circuit is normally open, means controlled from said machine proper to effect a relative movement between said primary elements to close said circuit, and means for concomitantly closing said clutch.

34. The combination of the machine proper, a motor for driving the same, said motor having a normally open circuit so as to be normally silent, a normally open clutch between said motor and the machine proper, circuit-closing means including, as two primary elements, a bridge and a pair of contacts or brushes, one of said primary elements mounted for revolution with said motor, clutch-closing means controllable by said revolving primary element, one of said brushes normally opposite a break in said bridge, whereby said motor circuit is normally open, means controlled from said machine proper to effect a relative movement between said primary elements to close said circuit and simultaneously close said clutch, said primary elements coöperating to keep said circuit closed during substantially an entire revolution of the revolving primary element, and means to arrest the revolving primary element to break the circuit and open the clutch.

35. The combination of the machine proper, a motor for driving the same, said motor having a normally open circuit, a

- normally open clutch between said motor and said machine proper, circuit-closing means including, as two primary elements, a bridge and a pair of contacts or brushes, one 5 of said primary elements mounted for revolution with said motor, clutch-closing means controlled by said primary elements, and one of said brushes normally opposite a break in said bridge, whereby said motor 10 circuit is normally open, means controllable from said machine proper for effecting a relative movement between said primary elements to close both the circuits and the clutch, a slip-connection or friction device 15 to connect said revolving primary element to said motor, and means to arrest the revolving primary element when it again reaches normal circuit-breaking position to open both said circuit and said clutch.
- 20 36. The combination of the machine proper, a motor for driving the same, a normally open clutch between said motor and said machine proper, said motor having a normally open electric circuit including 25 primary elements, one of which comprises a pair of brushes and the other of which comprises a bridge to be engaged by said brushes, said bridge having a gap normally opposite one of said brushes whereby said 30 circuit is normally open, a spring normally tending to move one of said primary elements to close said circuit, means to restrain said primary element, means operable from said machine proper for withdrawing said 35 restraining means, one of said primary elements having a slip-connection to said motor to revolve therewith, means for concomitantly closing said clutch, and means whereby said restraining means may be returned prior to the conclusion of the cycle 40 of operations of said machine proper to a position to intercept the revolving primary element and tension said spring.
37. The combination of the machine proper, of a motor for driving the same, said motor having an electric circuit, a normally open clutch between said motor and said machine proper, a pair of brushes and a bridge in said circuit, said bridge having 45 a gap normally opposite one of said brushes, whereby said circuit is normally open, a spring normally tending to move said bridge to close said circuit, a latch to restrain said bridge, said clutch between said motor and 50 said machine including a member adapted to drive said bridge by said spring, and means controllable from said machine proper for withdrawing said latch and concomitantly closing said clutch.
- 55 38. The combination of the machine proper, of a motor for driving the same, said motor having an electric circuit, a normally open clutch between said motor 60
- and said machine proper, a pair of brushes and a bridge in said circuit, said bridge having a gap normally opposite one of said brushes, whereby said circuit is normally open, a spring normally tending to move said bridge to close said circuit, a latch to restrain said bridge, means controllable 65 from said machine proper for withdrawing said latch, means whereby starting the motor effects concomitant closing of said clutch, and means for returning said latch to normal position in the path of said bridge and 70 concomitantly open said clutch.
39. The combination of the machine proper, a motor for driving the same, a train of gearing between said motor and said machine including a normally open 75 clutch, said motor being normally silent, a dog connected to revolve with said clutch and normally holding said circuit open and said clutch released, and means controlled from said machine proper for releasing said 80 dog for concomitantly starting said motor and connecting said clutch so as to connect said machine in driven relation with said motor at the same time that said motor is 85 excited to action.
40. The combination with a machine having a reciprocating portion, of a clutch comprising a member adapted to drive said machine, a pitman connected to said member of said clutch and said reciprocating 90 portion, a motor for driving said machine by said clutch, means whereby said clutch automatically breaks the power from said motor when the clutch is released and connects the power to said motor when the clutch is closed, and a friction slip clutch between said motor and said first-named clutch, adapted to slip when the said motor attempts to drive said pitman through an 95 overload.
- 100 41. The combination with a motor and a normally open circuit for driving it, of a reciprocating member adapted to be driven by said motor, a clutch for driving said reciprocating member, a pitman connected to said clutch and said reciprocating member, a dog included in said clutch, a key-controlled latch adapted to coöperate with said dog to hold the clutch open, means whereby said circuit is closed when said key-controlled latch is withdrawn, means whereby said clutch is closed when said circuit drives said motor, and a safety slip clutch between said first-named clutch and said motor adapted to slip when said motor attempts to 110 drive said reciprocating member through an overload.
- 115 42. The combination with a motor and a normally open circuit for driving it, of a reciprocating member adapted to be driven by said motor, a clutch for driving said reciprocating member, a pitman connected to said clutch and said reciprocating member, a dog included in said clutch, a key-controlled latch adapted to coöperate with said dog to hold the clutch open, means whereby said circuit is closed when said key-controlled latch is withdrawn, means whereby said clutch is closed when said circuit drives said motor, and a safety slip clutch between said first-named clutch and said motor adapted to slip when said motor attempts to 120 drive said reciprocating member through an overload.

JOHN N. THORNTON.
